(57) **CLAIM**

The ornamental design for a mower deck, as shown and described.

DESCRIPTION

FIG. 1 is a bottom perspective view of a mower deck, according to the present invention;

FIG. 2 is a top perspective view of the mower deck of FIG. 1;

FIG. 3 is a bottom plan view of the mower deck of FIG. 1; FIG. 4 is a top plan view of the mower deck of FIG. 1; FIG. 5 is a right side elevational view of the mower deck of FIG. 1;

FIG. 6 is a left side elevational view of the mower deck of FIG. 1;

FIG. 7 is a rear elevational view of the mower deck of FIG. 1; and,

FIG. 8 is a front elevational view of the mower deck of FIG. 1.

The dashed lines in the Figures are for environmental purposes only and do not form a part of the claimed design.

1 Claim, 6 Drawing Sheets
